LOUIS ELSBERG, OF NEW YORK, N. Y.

Letters Patent No. 73,176, dated January 7, 1868.

IMPROVED BUCKLE.

The Schedule referred to in these Letters Patent and making part of the same.

TO ALL WHOM IT MAY CONCERN:

Be it known that I, LOUIS ELSBERG, of the city, county, and State of New York, have invented a new and useful Improvement in Buckles; and I do hereby declare that the following is a full, clear, and exact description thereof, which will enable those skilled in the art to make and use the same, reference being had to the accompanying drawings, forming part of this specification.

The principal objects of this invention are—

First, to unite the two loops of the buckle, the one for the attached strap, and the other for the buckling-strap, in such a manner that traction on them in opposite directions draws the bar of the tongue and the buckling-loop into closer contact, and thereby holds the buckling-strap the more firmly. This result is accomplished by the angle which the attachment-loop forms with the plane of the buckling-loop, as well as by the curved form given to the plane of the whole buckle, the latter possessing the additional advantage of adapting it sometimes to particular uses.

Second, to prevent the tearing of the buckling-strap by piercing it with sharp points, as in ordinary buckles, or in most of those heretofore patented, which is accomplished by flattening the bar of the tongue and serrating its edge, or, which is equivalent thereto, by making the contact-surfaces of the tongue and buckling-loop with corresponding elevations and depressions. And

Third and last, to cheapen the manufacture of the buckle, by making both loops of wire, with the bar-tongue and attachment-loop of one continuous piece.

The buckle embraced in the present invention is formed of three parts, viz, a buckling-loop, an attachment-loop, and a bar-tongue, the buckling-loop being for the buckling-strap to pass through, the attachment-loop for the attached strap, and the bar-tongue for holding the buckling-strap in position where wanted. In the accompanying plate of drawings my improvements in buckles are illustrated—

Figure 1 being a side view of the buckle, and

Figure 2 a transverse section, taken in the plane of the line x x , fig. 1.

Similar letters of reference indicate corresponding parts.

A, in the drawings, represents the buckling-loop of the buckle. This loop is made of wire, with its extremities, B, bent at right angles to the middle portion C, which latter is flattened, with its edge D turned upward or raised along its length. E is the attachment-loop. This loop is made of a piece of wire, having its extremities F either angularly or circularly bent, with a small elbow, G, so that the ends are opposite and in the same direction as the main portion H. I is the bar-tongue, which, in the present instance, is made of the same piece of wire as the loop E, and forms a continuation of its circular-bent ends F, as shown, having its middle portion J flattened, with its upper edge K serrated and turned backward. To unite the buckling-loop to the attachment-loop, if the latter and the bar-tongue are made of one continuous piece of wire, the ends of the buckling-loop are bent upon themselves, to form a hook or eye, L, for holding the attachment-loop on each side. If the attachment-loop and bar-tongue are made separate, the buckling-loop may be either formed with eyes, as above described, or simply have holes made through its extremities, to receive the circular ends of the attachment-loop, and then to the eyes, or their equivalents, of the attachment-loop, the bar-tongue, similarly provided with eyes, hung. In either of the above forms of connections between the attachment and buckling-loops a movable joint is fixed.

In making the buckle with the loops above described, the plane of the attachment-loop is made to form an obtuse angle with the plane of the tongue, or the whole to form a curve from one side of the buckle to the other, as shown in fig. 2 of the drawings. The elbows at the ends of the attachment-loop may be dispensed with, and the ends of the buckling-loop bent directly over and around the attachment-loop. The contact-surface of both the bar-tongue and flattened portion of the buckling-loop may be formed with corresponding depressions and elevations, if so desired.

I claim as new, and desire to secure by Letters Patent—

The buckle, constructed as described, consisting of the buckling-loop A, having the flattened centre C, and bent edge D, its extremities B bent at right angles to the centre C, forming bearings for the loop E, the latter having the serrated tongue I fitting between the arms B upon the flat surface of the loop A, beneath the edge D, as herein described, for the purpose specified.
